HIGH FLAME-LOW FLAME BURNERS
William R. Irwin, P.O. Box 155, Boulevard Station,
Bronx, N.Y.

Continuation of abandoned application Ser. No. 196,414,
May 21, 1952. This application Nov. 29, 1963, Ser.
No. 327,145

20 Claims. (Cl. 158—28)

This invention relates to air and fuel supply systems and in particular it relates to a system for burning fuel wherein air to support the combustion of said fuel is supplied at either of a plurality of defined rates synchronized with the defined rates at which the fuel is delivered to the space provided for combustion of same.

The present application is a continuation in part of my prior applications, Ser. No. 794,344, filed Feb. 19, 1959 and since abandoned, and a continuation of application Ser. No. 196,414, filed May 21, 1962 and now abandoned.

An object of the invention is to provide an inexpensive, easily regulated and safe means for operating fuel burners under high and low, heating flame conditions.

Another object is to provide means whereby each start-up of a fuel burner may be accomplished under the low flame condition.

Heretofore numerous burners have been provided which were designed to operate with a multitude of flame sizes or to operate with a pilot flame of fixed size in conjunction with a modulating flame or flames, the pilot flame having no useful heating effect but the varying sizes of modulating flame being directed to this purpose. Other burners have been provided in which the louvers supplying air for the combustion of modulating volumes of fuel, modulated therewith. Some of the latter, of intricate and expensive design, have been satisfactory, but others using modulating air intake louvers, or louvers of the solenoid operated type, have been found to be generally inadequate, prone to get out of order, and sometimes dangerous.

It is a particular object of the invention to provide a burner of the most simple type, inexpensive, trouble free and devoid of gadgets, through which fuel and air may be supplied for the correct combustion of said fuel and whereby all the advantages of modulating operation may be obtained without the usual attendant disadvantages thereof.

Of special interest is the matter of supplying air at an exact rate off the tip of a calibrated nozzle or a device emitting oil or another fuel into a combustion space at a fixed rate in order that the provided air may support the emitted fuel in the combustion process so that the maximum amount of heat is extracted from same.

In simple terms, the last statement would mean that sizes and shapes of heating flames must conform to the dimensions of combustion spaces or fireboxes to the greatest possible degree and that an absolute minimum of excess be allowed in the air provided for the consumption of defined rates of fuel.

As it is impossible, at the present time, to burn two different rates of fuel in any particular combustion area of a given size and to obtain the same percent of efficiency at each rate, it is apparent that the optimum can be realized only when the heating apparatus is operated under the high flame condition and with said flame suited to the proportions of the area in which combustion takes place.

When a burner is operated for the low flame heating condition, a satisfactory degree of efficiency may be realized through the judicious selection of a fuel emitting device or nozzle that supplies fuel at a rate and in a form which, supported by air for combustion at the most exact possible, will when ignited conform in resultant flame

2

shape to the area of the combustion space to the greatest extent.

However, under the low flame condition, where fuel is burned in a space sized for a larger flame, the percent of combustion efficiency obtainable will be less than when said burner is operated under the high flame condition, all other things being equal.

Nevertheless, the disadvantages involved in underfiring a combustion space of a given size may be compensated for in various ways if adequate heating effect to the surfaces of said space, to boiler and furnace areas and other parts requiring heat from the combustion process, is provided.

This is in sharp contrast to applications in which a pilot flame is maintained that has no useful heating effect or in which the burner apparatus must be underfired at all times due to its nature. The idea is also contrary to the use of a burner apparatus which modulates either during its starting period, its shut-down or on its running cycle and which entails a large number of flames of different size.

All of the last mentioned factors have certain detrimental results which are well known, but they have been mentioned to dispel any thoughts of similarity engendered by the seeming likeness of actually disparate methods of combustion.

For a better understanding of the invention reference should be made to the accompanying drawings wherein like characters denote like or corresponding parts throughout the several views, and in which:

FIG. 1 is a diagrammatic representation of an oil burner with fuel and air supply systems in association with a simple electrical control system;

FIG. 2 is a diagrammatic representation of a solenoid operated flow control or flow directing valve;

FIG. 3 is a view taken after part of the embodiment shown in FIG. 1 with variations therefrom insofar as oil conduit and nozzle arrangements are concerned;

FIG. 4 shows an arrangement of oil bypass conduit means which differs from the bypass means shown in FIG. 1;

FIG. 5 is a more comprehensive view of an air check-valve means indicated in the embodiment of FIG. 1;

FIG. 6 is a diagrammatic representation of a "fuel unit," said unit type being an element in common use with means for the intake, filtering, pumping, pressure regulation and bypassing of fuel oil prior to the combustion of same;

FIG. 7 is a representation of an oil flow "cut-off" means by which pressure on a column of oil within a discharge conduit may be neutralized to prevent leakage of the oil from an emitting orifice after the actuation of the pressure imposing means has ceased.

Apart from the pressure regulating-bypass means depicted in the drawing of said fuel unit, additional pressure regulating means in association with other bypass and valve means are shown.

The illustration of a plurality of pressure regulating complexes may be regarded as unnecessary and redundant but same was undertaken with a view towards the possible use of newly developed fuels considered uncontrollable by ordinary methods. These fuels are no longer seriously contemplated but the parts shown require some explanation and in order to simplify same alphabetical indicia have been used for the manually operable valves of the embodiments, whereby the sequential operation of the different bypass means employed in conjunction with the control of oil pressures may be stated with brevity. Said explanation will be given at a later point.

Referring now to FIG. 1, an oil burner 10 schematically representative of the high pressure or "gun" type is

shown and a blower unit 11, fuel unit 12 and an electric motor 13 are components associated therewith. Said motor 13 is of the type that reaches full operational speed almost instantaneously upon energization and it provides rotation through shaft means for the wheel of the blower unit 11 and the stages of pumping gears positioned within said fuel unit 12.

Oil is supplied to an oil suction port of said fuel unit from an oil storage tank 14 by means of an oil suction conduit 15 extending therebetween. An oil conduit section 16 extends between the discharge outlet of the fuel unit to an inlet port of the solenoid operated flow regulating valve 17, and it is pointed out that said valve 17 could have two inlet ports rather than one as shown, for equivalent effect. Another oil conduit section 16a extends between conduit section 16 and the oil storage tank 14, another conduit section 24 is connected between a bypass outlet of said fuel unit and conduit section 24a, and said section 24a is connected between the suction conduit 15 and the oil return conduit 16a.

Two oil discharge conduit sections 18 and 19 are portrayed as extending from the discharge outlets of the flow regulating valve 17 and calibrated nozzles 21 and 20 are affixed respectively at the termini thereof.

A combination oil metering and pressure regulating valve 22 is interposed in conduit section 18 and a similar metering and pressure regulating valve 23 is interposed in conduit section 19. Each of the valves 22 and 23 have means integral therewith whereby they may be manually opened to the fullest extent so that they thereby become ineffective insofar as the regulation of pressure or the control of fuel flow is concerned.

A manually operable valve A is emplaced in conduit section 24 and a similar valve B is positioned in section 24a. Other, corresponding valves C and D are interposed in conduit section 16a.

From the bypass outlet of the valve 22 a conduit section 22a is indicated as extending to the storage tank 14 for returning excess oil thereto at such times as said valve 22 might be employed for the regulation of oil pressure. A manually operable shut-off valve G is interposed in section 22a and when the fuel unit 12 is used to regulate oil pressure, valve 22 is fully opened and valve G is closed, it being obvious that said conduit section 22a would not be required for bypass purposes at such time.

From the bypass outlet of valve 23 a conduit section 23a extends to conduit section 16a. A manually operable valve H is positioned in section 23a, and like valve G, said valve H is maintained in the closed position at all times except when valve 23 is used as a pressure regulating means and the fuel unit 12 is not employed for this purpose.

Because two calibrated nozzles 20 and 21 are provided in the embodiment being discussed, it is unlikely that the valves 22 and 23 would be needed at any time when a light fuel oil is the combustible. Likewise, valves E and F would not ordinarily be employed, except perhaps, to be closed at a time when said nozzles might be removed for cleaning or replacement.

When the fuel unit is relied upon for pressure regulation and excess oil is returned to the storage tank, the valves 22, 23, A, D, E and F are opened fully and the valves B, C, G and H are closed, said excess oil flowing to the tank through conduit sections 24, 24a and 16a.

With a similar arrangement except that valve B is opened and valve D is closed, excess oil may be returned to the suction conduit 15.

If the valves 22 and 23 should be used for regulating the pressure of the fuel delivered to the nozzles 20 and 21, say theoretically, at a time when the pressure regulating facilities of the fuel unit 12 may have been removed for repair but with the gear stages of said unit still serving as a pumping means, valves A, B, and C may be closed and valves D, E, F, G and H opened, with

said valves 22 and 23 being adjusted to maintain the desired rates of oil pressure in the conduits 18 and 19.

As oil leaves the solenoid valve 17 and passes through the conduit section 18 to be emitted from the nozzle 21, oil in excess of the desired rate will be returned from the bypass outlet of the valve 22 through the conduit section 22a and the opened valve G to the oil storage tank 14.

Under like conditions, when the valve 23 is regulating the pressure of the oil delivered to nozzle 20 through conduit section 19, excess oil will be returned to said tank from the bypass outlet of valve 23 through the valves H and D and the conduit sections 23a and 16a.

Other pressure regulating-bypass arrangements exist in the embodiment apart from the internal bypass means intrinsic to the fuel unit but inasmuch as the description of same would be superfluous it will be omitted.

In the embodiment of FIG. 3, wherein only one calibrated nozzle 68 is provided, a metering means additional to said nozzle is a necessity. In the figure the conduit sections 18 and 19 are joined at a conduit junction 66 and another conduit section 67 is connected thereto, the nozzle 68 being affixed at its terminus.

Regulating valve F in conduit 19 to be fully opened during operation and to be closed only when repairs are effected on the apparatus, valve E in conduit section 18 would be retained for the purpose of a secondary metering and pressure regulating device in said section 18 unless the fuel used required a valve of more complex type.

However, finding that said valve E was satisfactory for reducing the pressure of ordinary fuel oil and for maintaining a precise rate of flow in conduit section 18 against nozzle 68 for the low flame condition, said nozzle, if calibrated for a given pressure, could have applied thereagainst a higher rate of pressure, imposed on the fuel oil through said conduit section 19.

This would require that the fuel unit or other primary pumping-pressure regulating means be adjusted to deliver a higher pressure and rate of flow than is called for by the calibration specifications of said nozzle.

Figuratively speaking, if nozzle 68 is calibrated to deliver 10 gallons of #2 fuel oil per hour at a pressure of 100 p.s.i., and if the combustion space requires a high fire rate of 15 gallons per hour for maximum combustion efficiency, let it be said that a pressure of 150 p.s.i. applied to nozzle 68 would result in fuel oil being delivered therefrom at the required 15 gallon per hour discharge rate.

Hence if the adjusted fuel unit maintained a pressure of 150 p.s.i. in conduit section 19 against nozzle 68 said pressure would be reduced in conduit section 18 by adjusting the flow of oil therethrough by means of valve E. If said pressure were reduced to 100 p.s.i., oil would issue from said nozzle 68 via conduit section 18 at the nozzle's calibrated rate of 10 gallons per hour for the low flame condition.

It should not be considered that oil discharged from said nozzle at a pressure 50 p.s.i. in excess of its calibration would affect its firing capabilities adversely. Rather, when a nozzle is fired at a higher pressure than specified by the manufacturer the result is usually superior performance, although the life of the nozzle might be shortened to a minor extent.

It has been suggested that two different rates of oil cannot be properly fired from a nozzle designed for one specific rate. This would be true if the design rate were adhered to for the high flame condition and a much lower rate of pressure were used for the low flame condition. For example: A nozzle designed for a pressure of 100 p.s.i. would fire poorly if under a pressure of only 50 p.s.i.

In FIG. 4 the disposition of the various conduit sections differs from the arrangement used in FIG. 1 in that

fuel may be bypassed from the unit 12 only to the suction conduit 15, rather than to the storage tank 14.

When valve C is closed and valve A is maintained in the opened position, excess oil is bypassed from the fuel unit 12 through conduit sections 24 and 24b and is again indrawn to said fuel unit through the suction conduit section 15.

Upon bypass means internal to the fuel unit being used in association with other pressure regulating means therein, both of the valves A and C would be closed.

Valve C was intended as a secondary pressure regulating means to be employed with the volatile fuel mentioned previously, but as the use of said fuel is not presently feasible, said valve C should be considered as being always in the closed position. It is however, evident, that if a fuel exhibited instability after being discharged from a primary pumping-pressure regulating means that a secondary regulator such as valve C would be advantageous.

Returning to FIG. 1 in conjunction with the general description:

Other components include the ignition transformer 25, the high voltage terminals 26 at the output side thereof, the high tension insulated cables 27 connected at said terminals and extending therefrom, the metal igniters 28 affixed to the ends of said cables and porcelain sleeves 29 which cover and insulate said igniters except at their outer ends.

Upon application of electrical energy at ordinary voltage to the primary winding of the transformer, said energy is rectified to an ultra high voltage in the secondary winding thereof, the circuit of the secondary being completed only across the gap existing between the tips of said igniters, said high voltage bridging the gap by an intense spark which serves to light off the fuel in the air-fuel mixture supplied to the combustion space.

The primary blower 11 has an air door or shutter 30 with a knob 31 fastened thereto by which the position of said shutter may be easily adjusted to provide for indrawing the correct rate of ambient air to the suction side of the blower wheel 37 through the air intake ports 33. Once the shutter is positioned to admit the rate of air required for combustion it is fastened in place by any of the various types of fastening means commonly employed but which is was thought unnecessary to detail in the drawings.

The wheel 37 of said blower unit 11, upon being rotated by shaft means connected to the motor 13 when said motor is electrically energized, supplies the rate of air necessary to support combustion of the oil emitted by the calibrated nozzle 21 during the low flame operating periods or a portion of the air rate required during the high flame periods, air discharged off the tips of the wheel 37 passing through the air blast tube 70 to the space provided for combustion.

The auxiliary blower unit 32 has air intake ports 33 with a shutter pivotally positioned thereat whereby said ports may be opened to the desired extent to allow the correct rate of air to be indrawn when the motor 65 rotatably actuates the wheel of said unit through shaft means not illustrated in the drawings. Securing the shutter of the auxiliary blower would be made in the same manner applicable to the shutter of the primary blower.

When the wheel of the blower unit 32 is actuated, the air discharged therefrom goes through the air discharge passageway 35 of said unit to the air tube 36 and thence into the blast tube 70 wherein it augments the air discharged from the wheel of the primary blower unit 11 and wherefrom the combined air discharge of the blower plurality enters the combustion space to be intermixed with the high rate of oil discharged thereto from the nozzle 20 to support the combustion of said high rate of oil.

A gravity biased damper or check valve 71 may be

placed in the air tube 36 to prevent the escape of air discharged by the wheel 37 of the primary blower unit 11 through said tube and through the air ports 33 of the auxiliary blower unit during the low flame operating periods in which the motor 65 and the wheel of said auxiliary blower unit would not be actuated. Upon cessation of rotation of the wheel of the auxiliary blower unit 32 following the high flame periods, the blade 73 of said check-valve 71, if used, closes by gravity forces.

When employed, the blade 73 of said check-valve 71 will swing to the opened position only when the motor 65 rotates the wheel of the auxiliary blower unit 32, the air discharged from said wheel forcing the blade 73 to its opened position.

The electrical control system for the apparatus has been simplified in order to illustrate the basic ideas clearly. Said system consists of mercury switches 39 and 40 which may be actuated to their "on" or circuit making positions by the lessening of steam pressures within the boiler, a manually operable switch 41 which connects the operating system to a line voltage source at L, an electrical conduit 43 which is indicated as extending to the motor 13 and the transformer 25, another electrical conduit connected between conduit 43 and the #1 terminal of a relay switchboard 42, a bimetallic blade 44 pivotally connected to said terminal #1 and which may be actuated to establish connection terminals #1 and #2 of said switchboard through warping action caused by the reception of heat given off by a coil 45, said coil having a high electrical resistance and which is connected between terminals #1 and #3 of said switchboard, said terminal #3 having a connection directly to ground.

An electrical conduit section extends from said terminal #2 to one side of the mercury switch 40 and when said switch is in the closed position and the circuits of the system are otherwise closed power may be immediately transmitted through said section to energize the motor 65 and the solenoid winding of the flow regulating valve 17.

The upper passageway of said valve 17 is normally opened allowing for the flow of oil through same to the nozzle 21 for the low flame condition but upon said solenoid winding being energized in response to a call for the high flame said normally opened upper passageway is closed and the normally closed lower passageway is opened to allow the high rate of oil flow therethrough to the nozzle 20.

The solenoid operated flow regulating or flow directing valve 17 is particularized more clearly in FIG. 2, said figure showing glands 48 placed in two of the flat horizontal surfaces of the valve's inner structure to allow for the free vertical movement of the stem 49 but preventing leakage of oil from one valve compartment to another. The stem has affixed thereon closure discs 50 and 51 and when the valve's solenoid winding 46 is energized said stem 49 is snapped upwards against the pressure exerted by an expansion spring 47, said spring being positioned between a retaining plate 52 attached to said stem and the underside of a cover 64 used to protect the solenoid winding.

With the upward movement of the stem the closure disc 50 covers the valve seat orifice 60 and simultaneously the closure disc 51 is withdrawn from the lower seat orifice 59, thereby opening the normally closed lower passageway and closing the normally opened upper passageway of said valve.

The external surfaces of the valve body 53 is formed in part to encompass the valve intake port 54 and the discharge ports 61 and 62. Said intake port 54 communicates with the valve entrance chamber 55, the walls of which are formed in part by elements 58 and 63 of the internal web of said valve.

Said web also forms in part the valve discharge chambers 56 and 57 and holes drilled through the horizontal

surfaces of the web complex are polished to form the said orifices 59 and 60 or are used for the insertion of the glands 43.

The normally opened upper passageway of the valve comprises the intake port 54, the entrance chamber 55, the orifice 69, the discharge chamber 57 and the exit port 61.

The normally closed lower passageway comprises entrance port 54, chamber 55, the orifice 59, the discharge chamber 56 and the exit port 62.

It should be understood that the solenoid valve depicted is but indicative of a well known type and it is not presumed to detail the actual construction of same.

The fuel unit embodied diagrammatically in FIG. 6 is of the double gear stage type, although a single stage unit might suffice for most oil burning installations. Modern day fuel units are extremely compact, efficient, almost trouble free and maintain pressures of oil delivered to nozzles or other emitting orifices at very precise rates.

While fuel units are one of the best known elements commonly incorporated into oil burning systems, explanation is made here for the benefit of those not familiar with same that the gear stages and other components thereof, depicted widespread in the drawing, actually would be fitted into a small housing and have but one shaft means. Likewise, numerous of the components depicted could have substitutions made therefor.

In the embodiment the oil suction conduit 15 extends from the storage tank 14 to an oil filter device 140 and when the unit is actuated oil is drawn through same to conduit 141 which extends between said filter device and a first gear or suction gear stage 142; from the first stage 142 the indrawn oil passes through conduit section 143 into a bypass component 144 which has two entrance ports and two discharge ports; from the discharge port 145 the oil is passed into and through conduit section 146 to the low pressure side of a second gear or discharge gear stage 148. The oil is discharged from said second gear stage through a passageway 149 and into an element 150, said element having incorporated therein various constituent parts for the regulation of oil pressure. In the lower part of element 150, designated for convenience as chamber 151, the said oil is subjected to regulation of pressure by a needle valve 152 in association with a piston which has an orifice 154 communicating with a channel 155 drilled in and through said piston.

The piston 153 is positioned within the element 150 and is freely movable therein despite very close tolerance between said piston and the confining means of said element. A spring 156 is positioned to oppose movement of the piston with the ends thereof being in continuous engagement with the upper surface of the piston and with a fixed plate 157 respectively. An adjustment screw 158 is placed in contact with said plate with said screw extending through the casing at point 159 of the element. The screw 158 upon being turned inwardly against plate 157 causes greater compression of the spring 156 with resultant greater pressure on the oil delivered to the discharge conduit 16 connected to and extending from element 150.

The tip 160 of said needle valve 152 is in vibrating contact with the orifice 154 of the channel 155 drilled through said piston and upon a fluctuation of oil pressure in chamber 151 the vibrating contact between the orifice 154 and the needle valve tip 160 is varied accordingly so as to maintain a precise rate of pressure on the oil discharged into conduit 16.

Excess oil, determined in extent by the pressure maintained in the chamber 151 by the setting of the pressure regulating adjustment screw 158, travels through the channel 155 of said piston to the upper part of the interior of the element 150 and is discharged therefrom into a passageway 161 and thence into the bypass component 144 wherefrom it is either returned to the storage tank 14 via conduit 24 or it is again drawn into the second gear stage

148 to be recirculated into said chamber 151 of element 150.

If the discharge conduit section 16 were to be closed off while the gear stages of the fuel unit were in rotation, oil would pass from the first gear stage to the bypass component and part of the oil body would be returned to said tank 14 through conduit 24. Other parts of said oil body would recirculate through the second gear stage to element 150, through the latter into conduit 161, either again to be recirculated or to pass into conduit section 24 and thence to said tank.

Oil returned to the tank from the fuel unit through conduit 24 would of course be replaced by oil drawn from said tank through the suction conduit 15.

Numerous diversifications exist in the design of fuel units with approximately the same end result being obtained and it is not an object of the invention to disclose anything novel regarding same, but rather, to explain how such a unit would be employed with burner apparatus as embodied herein.

Oil flow cut-off means are particularized to some extent in FIG. 7 and although such means are very well known it is believed that a brief explanation of the function of same will not be amiss.

Said cut-off means are commonly employed to prevent oil from dripping from a nozzle or other emitting orifice after the pressure imposing means applied to the fluid have ceased actuation. Some form of flow cut-off means are necessary for almost all fluid fuel burners and particularly for oil burners of the automatic type, and such means would be a requirement for the burner elements as embodied in FIGS. 1, 3 and 4.

The body 170 of the oil flow cut-off component could be connected into the discharge conduit sections 18 or 19 as embodied in the last said figures but preferably it is interconnected immediately adjacent to the nozzle as shown in FIG. 3 whereat it is interposed in the discharge conduit section 67 adjacent to the calibrated nozzle 68 and as it is shown in the specific figure relating to cut-off means wherein the nozzle is designated by the number 20.

In the figure an oil passageway 171 extends within the component 170 as a continuation of an oil discharge conduit designated as 18, to an interior wall surface 172 therewithin. A plate 173 is easily slidable within a chamber 174 formed in said component 170, subject to a predetermined pressure being imposed thereon, with a very close tolerance existing between said plate 173 and the confines of said chamber. Said plate 173 is part of a unitary piece incorporating also a valve closure element 175 and a stem 176.

A pressure regulating plate 177 is permanently positioned by thread means within said chamber 174 and a cavity 178 is fashioned in but not through said plate 177 wherein said stem 176 is intromittent. A spring 179, compressible at about 50 p.s.i. of pressure encircles said stem with one end of said spring in engagement with the fixed plate 177 and the other in engagement with the slidible plate 173.

An oil channel 180 is drilled through a wall 181 of the component body 170 and said channel communicates with the said calibrated nozzle screwed to an anterior part of said body.

When oil under pressure enters the passageway 171 and said pressure is transmitted to the wall surface 172 and the face of the plate 173, the said unitary piece is forced backwards with the stem 176 passing into the cavity 178, providing that the pressure imposed on the oil is greater than the pressure exerted by the spring 179.

When actuation of the oil pumping means or other pressure imposing means ceases, the said unitary piece is forced forward by the pressure exercised by spring 179 and the closure element 175 covers the inner orifice of the oil channel 180 to prevent the flow of oil through the nozzle 20 during burner "off" periods.

Oil flow from the nozzle during periods when the pres-

sure imposing means is not actuated is known in the trade as "after drip" and for many years a wide variety of oil flow "cut-off" means have been available, the cut-off means illustrated being only indicative of the general purpose and application of same.

Using arbitrarily chosen figures for the settings of the switches or actuators through which the equipment is controlled, the operation of the system depicted in FIG. 1 would occur as follows:

With mercury switch 39 set to cut out at 15 p.s.i. of steam pressure and to cut in at 14 p.s.i. and all points below, and with mercury switch 40 set to cut out at 10 p.s.i. and to cut in at 9 p.s.i. and all points below, with the indicated boiler at room temperature said switches 39 and 40 would be in the "on" or circuit making position.

When the manually operable switch 41 is closed to connect the burner circuits through switch 39 to the line voltage source, power is immediately transmitted to the motor 13 and transformer 25.

The energized motor 13 almost instantaneously rotates at constant speed the gear stages of the fuel unit 12 and the wheel 37 of the primary blower 11 and oil is drawn from the storage tank 14 via the suction conduit 15 to said fuel unit and is discharged therefrom through conduit section 16 to the inlet port 54 of the flow regulator 17, into chamber 55 thereof, through the normally opened orifice 60, valve chamber 57, the discharge port 61 of said regulator 17 and thence into conduit section 18.

The oil flows in conduit 18 through the fully opened valves E and 22, through the cut-off component 170 and into the calibrated nozzle 21 from which it is emitted at a precise rate in the form of a very fine cone shaped spray into a combustion space, not shown.

Air metered at a precise rate through the air intake ports 38 of blower unit 11 and discharged off the wheel 37 thereof into and through the blast tube 70 into said combustion space, is there intermixed with the oil discharged from nozzle 21 whereat it supports the combustion of said oil for the low flame condition.

Oil in excess of the rate maintained by the pressure regulating means incorporated in the fuel unit 12 is discharged from said unit via the bypass conduit 24, through valve E, the bypass conduit sections 24a and 16 and valve D to the oil storage tank 14. At this time valves B, C, G and E are fully closed.

The oil in the air-oil mixture is instantly ignited by the spark caused to exist across the air gap at the tips of the igniter pair 28 through energization of the transformer 25.

At the same moment that the motor 13 and the transformer 25 are electrically energized, power is transmitted from conduit 43 to terminal #1 of switchboard 42 and the high resistance coil 45 connected between terminals #1 and #3 of said switchboard begins to generate heat and said heat causes the warp switch blade 44 to begin moving towards its closed position across terminals #1 and #2.

After a predetermined interval said blade 44 completes its movement and establishes connection across said terminals #1 and #2 and electrical energy is immediately transmitted through the closed mercury switch 40 to the windings of the motor 65 and the solenoid 46 of the flow regulating valve 17.

The wheel of the auxiliary blower unit 32 is thereupon rotated almost instantaneously by said motor 65 and ambient air is indrawn through the air intake louvers 33 by said wheel and is discharged therefrom at a defined rate through the discharge casing 35 and into and through the air tube 36 whereby the damper 71 is forced into the opened position if employed. From tube 36 the air from said auxiliary blower enters the blast tube 70 wherein it is combined with the discharge air from the primary blower unit 11 and wherefrom the combined discharge of the primary and auxiliary blower units is forced, at a defined rate, into said combustion space to support therein the

combustion of the high rate of oil for the high flame condition.

The solenoid winding 46 of the flow regulating valve 17, energized simultaneously with the motor 65, causes the stem 49 of said valve 17 to be snapped to its actuated position and the closure disc 50 thereof covers the normally opened orifice 60 while the closure disc 51 is removed from its normal position of closing over orifice 59. The flow of oil through the normally opened upper passageway of the regulating valve 17 and to the nozzle 21 is stopped and concurrently oil immediately issues from the calibrated nozzle 20, said nozzle 20 having an orifice designed for the high rate of oil flow therethrough with the passage to said orifices being through the normally closed, lower passageway of said valve 17 and via conduit section 19 and the fully opened valves F and 23.

The burner apparatus under the stated circumstances would be operating under the high flame condition and would continue thereunder until the cut-out setting of mercury switch 40 was reached.

Upon switch 40 being actuated to its off position by a boiler steam pressure of 10 p.s.i., the burner apparatus would again resume its operation under the low flame condition, the motor 65 and the solenoid 46 of the regulator 17 being deenergized by the actuation of said switch.

Then, depending upon whether or not the apparatus was being used for comfort heating or an industrial process, the dispersal of heat generated in comparison with the size of the combustion space, and numerous other factors, the burner apparatus would either continue to raise the pressure of steam in the boiler under the low flame condition at a greatly decelerated rate until the 15 p.s.i. cut-out point of the mercury switch 39 was reached and whereat the burner would be completely shut down and so remain until said switch 39 again reached its cut-in point of 14 p.s.i., due to lessening of steam pressures in the boiler, or, if the load on the boiler were such that the steam pressures thereof diminished when the burner operated under the low flame, upon said pressure diminishing slowly from the 10 p.s.i. cut-out point to the 9 p.s.i. cut-in point of mercury switch 40 said burner apparatus would again revert to the high flame condition.

Under the last stated circumstances the burner would remain in operation continuously and the boiler steam pressure would vary only by a differential of one pound, or, between 9 and 10 p.s.i.

The oil flow cut-off means 170 and 170a, interposed in the oil discharge conduit sections 18 and 19 respectively, apart from preventing drip of oil from the nozzles 21 and 20 when the pressure imposing means of the fuel unit had ceased actuation, would also prevent leakage from an associated nozzle when the other of said nozzles was delivering oil under pressure therefrom.

Results from burner operation wherein only one nozzle is employed, as in FIG. 3, would be the same as described for the operation of the burner embodied in FIG. 1, requiring only that means as already detailed or similar, must be used to provide the two rates of oil flow through the nozzle 68.

Continuous operation of the apparatus over long periods without a complete shut-down would result in substantial savings of fuel, and in processing, wherein temperature ranges might have to be held within very narrow limits, the benefits of operation as described would be exceptional. Other economies would result through prevention of wear and tear on equipment, it being well known that constant stopping, recycling and restarting will cause same to have a comparatively short life.

The selection of a combustion space or firebox relative to a boiler of a given horsepower, and the size, shape and placement of the flames to be used therewith demands the most expert and critical judgment and it is in these respects that the application of knowledge and experience can gain the economies and other advantages possible. Without

11

such application all of these benefits can be easily reduced in scope or lost entirely.

Although the system of controls used in the embodiments is minimal to expedite description, numerous adjuncts may be incorporated therewith to enhance the performance of the apparatus.

Among such adjuncts would be an air switch or the like that would automatically ascertain that the high rate of air was being supplied for the high flame condition before the solenoid winding 46 of the flow regulating valve could be energized to provide the high rate of oil to the combustion space.

Time delay means, used with many solenoid operated devices, could also be incorporated with said flow regulating valve 17 to allow sufficient time for the high rate of air to be supplied to said combustion space before said valve 17 could be actuated to allow the high rate of oil to be delivered therethrough.

Other elements, numerous in number, directed either to safer or better operation, could be used with the disclosure as a matter of choice.

Realizing that the embodiments herein diagrammatically illustrated are susceptible of many other applications and that modifications may be made in the arrangement and structure of the elements without departing from the spirit and scope of the invention, I do not wish to be limited except by the scope of the appended claims.

I claim:

1. A high rate, low rate heating system having in combination: burner means, fuel pumping and pressure regulating means, excess fuel bypass means associated with said pressure regulating means, a flow directing valve, fuel conduit means extending from the output side of said pumping means to intake port means of said valve, a normally opened and a normally closed passageway through said valve, automatically actuatable means to close said normally opened passageway and to simultaneously open said normally closed passageway, said burner means including a first fuel conduit extending from the exit port of said normally opened passageway of said valve, a first calibrated nozzle at the terminus of said first fuel conduit, a second fuel conduit extending from the exit port of said normally closed passageway of said valve, a second calibrated nozzle at the terminus of said second fuel conduit, an air blast tube leading to said nozzles to deliver combustion air to the fuel emitted thereby, a primary blower having means for the intake of ambient air and air rate regulation means and with air discharge means connected to said blast tube, an auxiliary blower having means for the intake of ambient air and air rate regulation means and with air discharge means connected to said blast tube, a first constant speed electric motor for actuating said pumping means and said primary blower, a second constant speed electric motor for actuating said auxiliary blower, first automatic control means individual to said first electric motor, and second automatic control means common to said second electric motor and the automatically actuatable means associated with said passageways; and, responsive to a requirement for a low rate, low flame heating condition, said first automatic control means being adapted to cause the energization of said first electric motor and the actuation thereby of said primary blower and said pumping means to cause a defined, low rate of fuel to issue from said first calibrated nozzle and with said primary blower discharging a defined, low rate of air through said blast tube to support said low rate of fuel in combustion; and, responsive to a requirement for a high rate, high flame heating condition, said second automatic control means being adapted to cause the energization of said second electric motor and said automatically actuatable means to thereby open said normally closed passageway and to simultaneously close said normally opened passageway of said valve and to cause a defined, high rate of fuel to issue from said second calibrated nozzle, and with the actuated auxiliary

12

blower discharging a defined rate of air into said blast tube to augment the defined rate of air discharged by said primary blower, the combined air discharge rates of said primary and auxiliary blowers issuing from said blast tube as a defined, high rate of air to support said high rate of fuel in combustion.

2. A system according to claim 1, including normally closed air valve means between the discharge means of said auxiliary blower and said air blast tube, said air valve means preventing escape of discharge air from said primary blower when a requirement is made for the low flame condition, said air valve means opening when a requirement is made for the high flame condition.

3. A system according to claim 1, in which the resistance to flow of said bypass means and the resistance to flow through said first calibrated nozzle determines in proportionate ratio the rate of fuel delivery for the low flame condition, and resistance to flow of said bypass means and the resistance to flow through said second calibrated nozzle determines in proportionate ratio the rate of fuel delivery for the high flame condition.

4. A system according to claim 1, having control means whereby said system makes each start-up after a complete shut-down under the low flame condition.

5. A system according to claim 1, having fuel flow cut-off means for said first calibrated nozzle and said second calibrated nozzle whereby fuel may not be discharged from said first nozzle or from said second nozzle unless said cut-off means have been actuated to allow the flow of fuel therethrough.

6. A high rate, low rate heating system having in combination: burner means, fuel pumping and pressure regulating means, excess fuel bypass means associated with said pressure regulating means, a flow directing valve, fuel conduit means extending from the output side of said pumping means to intake port means of said valve, a normally opened passageway through said valve extending to a discharge port thereof, a normally closed passageway through said valve extending to a discharge port thereof, automatically actuatable means to close said normally opened passageway and to simultaneously open said normally closed passageway, said burner means including fuel conduit means extending from said discharge ports to a place of destination whereat fuel may be emitted for combustion, automatic metering means associated with last said conduit means whereby either a regulated, defined low rate or a regulated, defined high rate of fuel may be emitted at said place of destination, calibrated nozzle means associated with last said conduit means at said place of destination, an air blast tube leading to said nozzle means to deliver combustion air to the fuel emitted thereby, a primary blower having means for the intake of ambient air and air rate regulation means and with air discharge means connected to said blast tube, an auxiliary

50 blower having means for the intake of ambient air and air rate regulation means and with air discharge means connected to said blast tube, a first electric motor for actuating said pumping means and said primary blower, a second electric motor for actuating said auxiliary blower, a first automatic control means individual to said first electric motor, a second automatic control means common to said second electric motor and said automatically actuatable means; and, responsive to a requirement for a low rate, low flame heating condition, said first automatic control means being adapted to cause the energization of said first electric motor and the actuation thereby of said primary blower and said pumping means to cause a defined, low rate of fuel to issue from said calibrated nozzle means and with said primary blower discharging a defined, low rate of air through said blast tube to support said low rate of fuel in combustion for the low flame heating condition, and, responsive to a requirement for a high rate, high flame heating condition, said second automatic control means being adapted to cause the energization of said second electric motor and

55 60 65 70 75

the actuation of the automatically actuatable means associated with the passageways of said valve to thereby cause the opening of said normally closed passageway and the closing of said normally opened passageway thereof and to cause a defined high rate of fuel to issue from said calibrated nozzle means, and with the actuated auxiliary blower discharging a defined rate of air into said blast tube to augment the defined rate of air discharged by said primary blower, the combined air discharge rates of said primary and auxiliary blowers issuing from said blast tube at said place of destination as a defined, high rate of air to support said defined, high rate of fuel in combustion.

7. A system according to claim 6, including normally closed air valve means between the discharge means of said auxiliary blower and said air blast tube, said air valve means preventing escape of discharge air from said primary blower when a requirement is made for the low flame condition, said air valve means opening when a requirement is made for the high flame condition.

8. A system according to claim 6, having control means whereby said system makes each start-up after a complete shut-down under the low flame condition.

9. A system according to claim 6, having fuel flow cut-off means whereby fuel may not be discharged from said nozzle means unless said cut-off means have been actuated to allow the flow of fuel therethrough.

10. A system according to claim 6 in which said nozzle means comprise a single calibrated nozzle.

11. A high rate, low rate heating system having in combination: burner means, a fuel supply source, fuel conduit means extending from said source to a place of destination whereat fuel may be emitted for combustion, fuel pressurizing means associated with said conduit means for effecting pressure on fuel therein, automatic metering means associated with said conduit means whereby a regulated low rate or a regulated high rate of fuel may be emitted at said place of destination, automatic valve means associated with said conduit means to allow either said regulated low rate or said regulated high rate of fuel to flow to a point of emission at said place of destination, an air blast tube associated with said burner means and leading to said place of destination, a primary blower having means for the intake of ambient air and the rate regulation thereof and with air discharge means connected to said blast tube, an auxiliary blower having means for the intake of ambient air and the rate regulation thereof and with air discharge means connected to said blast tube, a first automatic control means common to said primary blower and said fuel pressurizing means, a second automatic control means common to said auxiliary blower and said automatic valve means; and, responsive to a requirement for a low rate, low flame heating condition, said first automatic control means being adapted to cause the actuation of said primary blower and said fuel pressurizing means whereby said regulated low rate of fuel is supplied to a point of emission at said place of destination and a defined, low rate of air is discharged through said blast tube to support said low rate of fuel in combustion at said place of destination, and, responsive to a requirement for a high rate, high flame heating condition, said second automatic control means being adapted to cause the actuation of said auxiliary blower and said automatic valve means, said actuated automatic valve means stopping the flow of said regulated low rate of fuel and causing said regulated high rate of fuel to be supplied to a point of emission at said place of destination and the actuated auxiliary blower discharging a defined rate of air into said blast tube to augment the defined rate of air discharged by said primary blower, the combined air discharge rates of said primary and auxiliary blowers forming a defined, high rate of air to support said high rate of fuel in combustion at said place of destination.

12. A system according to claim 11, including normally

closed air valve means between the discharge means of said auxiliary blower and said air blast tube, said air valve means preventing escape of discharge air from said primary blower when a requirement is made for the low flame condition, said air valve means opening when a requirement is made for the high flame condition.

13. A system according to claim 11, having control means whereby said system makes each start-up after a complete shut-down under the low flame condition.

14. A system according to claim 11 having fuel flow cut-off means whereby fuel may not be emitted at said place of destination until said cut-off means have been actuated to allow the flow of fuel therethrough.

15. A high rate, low rate heating system having in combination: burner means, a fuel supply source, fuel conduit means extending from said source to a place of destination whereat fuel may be emitted for combustion, fuel pressurizing means associated with said conduit means for effecting pressure on fuel therein, automatic metering means associated with said conduit means whereby a metered low rate or a metered high rate of fuel may be emitted at said place of destination, a flow directing valve associated with said conduit means, a normally opened and a normally closed passageway through said valve, automatically actuatable means associated with said valve to close said normally opened passageway and simultaneously to open said normally closed passageway whereby said metered low rate or said metered high rate of fuel may pass to a point of emission at said place of destination, an air blast tube associated with said burner means and leading to said place of destination, blower means having therewith means for the intake of ambient air and air discharge means connected to said blast tube, manually adjustable metering means associated with said blower means for providing a metered low rate or a metered high rate of air to said blast tube, automatic regulating means associated with said blower means whereby said metered low rate or said metered high rate of air is delivered to said blast tube and therethrough to

30 said place of destination, a first automatic control means common to said fuel pressurizing means and said blower means, and a second automatic control means common to said automatically actuatable means associated with said valve and to said automatic regulating means associated with said blower means; and, responsive to a requirement for the low rate, low flame heating condition, said first automatic control means being adapted to cause the actuation of said fuel pressurizing means and said blower means to cause a metered low rate of fuel to be emitted at a point of emission at said place of destination and to cause a metered low rate of air to be supplied to said blast tube and therethrough to said place of destination to support the combustion of said metered low rate of fuel; and, responsive to a requirement for the high rate, high flame heating condition, said second automatic control means being adapted to cause the actuation of the automatically actuatable means associated with said valve and said automatic regulating means associated with said blower means to thereby stop the emission of said metered low rate of fuel and to cause a metered high rate of fuel to be emitted at a point of emission at said place of destination and to cause a metered high rate of air to be supplied to said blast tube and therethrough to said place of destination to support the combustion of said high rate of fuel.

65 16. A system according to claim 15, having control means whereby said system makes each start-up after a complete shut-down under the low flame condition.

70 17. A system according to claim 15 having fuel flow cut-off means whereby fuel may not be emitted at said place of destination unless said cut-off means have been actuated to allow the flow of fuel therethrough during periods requiring combustion of said fuel.

18. A high rate, low rate heating system having in combination: burner means, a fuel supply source, fuel con-

duit means extending from said source to a place of destination whereat fuel may be emitted for combustion, fuel pressurizing means associated with said conduit means for effecting pressure on fuel therein, automatic metering means associated with said conduit means whereby a metered low rate or a metered high rate of fuel may be emitted at said place of destination, an electrically operative flow directing valve associated with said conduit means, a normally opened and a normally closed passageway through said valve, electrically actuated means to close said normally opened passageway and simultaneously to open said normally closed passageway whereby either said metered low rate or said metered high rate of fuel may pass through said valve to a point of emission at said place of destination, blower means having therewith means for the intake of ambient air and air discharge means leading to said place of destination, manually adjustable metering means associated with said blower means for providing a metered low rate or a metered high rate of air through said air discharge means, regulating means associated with said blower means whereby either said metered low rate or said metered high rate of air is discharged through said air discharge means to said place of destination, a first automatic control means common to said fuel pressurizing means and said blower means, and a second automatic control means common to the electrically actuated means of said valve and the regulating means associated with said blower means; and, responsive to a requirement for the low rate, low flame heating condition, said first automatic control means being adapted to cause the actuation of said fuel pressurizing means and said blower means whereby a metered low rate of fuel in flow through said flow directing valve is emitted at a point of emission at said place of destination

25

30

and whereby a metered low rate of air is discharged through said discharge means associated with said blower means to said place of destination to support said metered low rate of fuel in combustion; and, responsive to a requirement for the high rate, high flame heating condition, said second automatic control means being adapted to cause the actuation of said electrically actuated means of said valve and the actuation of said regulating means associated with said blower means whereby a metered high rate of fuel in flow through said flow directing valve is emitted at said place of destination and whereby a metered high rate of air is discharged through said discharge means associated with said blower means to said place of destination to support said metered high rate of fuel in combustion.

19. A system according to claim 18, having control means whereby said system makes each start-up after a complete shut-down under the low flame condition.

20. A system according to claim 18, having fuel flow cut-off means whereby fuel may not be emitted at said place of destination unless said cut-off means have been actuated to allow the flow of fuel therethrough for combustion.
